UNITED STATES PATENT OFFICE.

DELBERT J. BRANNING, OF HAWLEY, PENNSYLVANIA.

DESIGN FOR A GLASS VESSEL.

43,665.

Specification for Design.

Patented Mar. 4, 1913.

Application filed November 13, 1912. Serial No. 731,186. Term of patent 3½ years.

To all whom it may concern:

Be it known that I, DELBERT J. BRANNING, a citizen of the United States, and a resident of the city of Hawley, county of Wayne, and State of Pennsylvania, and whose post-office address is Keystone and Spring streets, in said city, have invented a new, original, and ornamental Design for a Glass Vessel, of which the following is a specification.

Reference is to be had to the accompanying drawing in which:

Figure 1 is a plan view of a glass vessel

embodying my design; and Fig. 2 is an elevation of the same.

I claim:

The ornamental design for a glass vessel as shown herein.

Signed at the city of Hawley, county of Wayne, and State of Pennsylvania, this 7th day of November, 1912.

DELBERT J. BRANNING.

Witnesses:

R. W. MURPHY,
GEO. W. MURPHY.
